DRYING OF HOLLOW CONTAINERS

E. Roy Alling, Kenmore, and Carl F. Ulrich,
Buffalo, N. Y.; said Ulrich assignor to Rice &
Adams Corporation, Buffalo, N. Y.

Application February 26, 1941, Serial No. 380,682

17 Claims. (Cl. 34—165)

This invention relates to the drying of hollow containers and particularly to those having substantially restricted mouths or passageways communicating with the interior thereof. Containers of this type for which this invention is particularly useful are the milk cans for conveying fluid milk from the producers to the receiving plant, it being necessary that such cans after the milk is emptied be thoroughly washed, sterilized and dried before being returned to the producer.

Can washers commonly used for this purpose guide the cans, with their covers removed, in inverted positions along a selected path by a step by step movement, with substantial periods of rest in selected treating stations between movements. Heretofore, it has been customary to dispose a pipe below said path for directing upwardly into the inverted cans different treating fluids, the last of which is a stream of hot, dry air. Such a stream of hot air is under relatively low pressure, and, in order to dry the containers within the relatively short interval of time available in a treating station, the cross sectional area of the stream must be relatively large with respect to the size of the open mouth of the can. Because of the restricted opening of the can at its mouth, the delivery of such an upwardly directed stream of hot air has heretofore not produced an adequate drying action, and according to this discovery, this apparently has been due to the fact that the air within the can acts as a compression chamber or baffle which resists the entrance of a stream of hot air, with the result that much of the stream is merely deflected laterally and only a minor amount actually enters the can where it must diffuse through the mass of wet air within the can and exert its drying effect.

One object of this invention is to provide improved mechanism for drying hollow containers.

Another object of this invention is to provide an improved device for drying cans with an air stream, in which resistance to flow of air passing through the necks of said cans will be reduced to a minimum, in which the air will flow in intimate drying contact with all of the interior surfaces of said cans and which will be effective in operation, and relatively inexpensive.

Another object of this invention is to provide an improved device for drying milk cans which will be positive and effective in operation, and which may be readily adapted for use on can or container washers previously installed as well as on new washers.

A further object of this invention is to provide improved means for drying the interiors of hollow containers such as milk cans, with which a more effective and rapid drying of the entire interior of the can is possible within a given interval of time, with which the drying gas will be more effectively utilized in drying the cans, which may

be incorporated in existing types of can washers without material changes in their design as to other details of treatment, with which the capacity of the machine in handling cans need not be materially diminished, and which will be relatively simple, compact, durable, dependable and inexpensive.

Another object of the invention is to provide improved means for drying the interiors of containers, with which the danger of injury to the containers will be reduced to a minimum in the event of misplacement of a container.

Various other objects and advantages will be apparent from the following description of an embodiment of the invention, and the novel features will be particularly pointed out hereinafter in the appended claims.

In the accompanying drawings:

Fig. 1 is a side elevation with parts broken away, of part of a can washer constructed in accordance with my invention, and showing several washing and drying stations;

Fig. 2 is a somewhat diagrammatic elevation of a part of a can washer, showing the air intake and heater for the drying air which is used to dry cans;

Fig. 3 is a side elevation, partially in section, of part of the drying mechanism of a washer, illustrating the position of the cans in drying stations, with the rising jets or nozzles retracted, just as the cans are about to be advanced forward;

Fig. 4 is a somewhat similar view of the same showing the cans while at rest in drying positions with the rising jets or spouts inserted through the necks of the cans into the interior thereof.

Fig. 5 is a sectional elevation of part of a washer, showing the position of the air ducts and blower which provide the drying air to cans in a washer;

Fig. 6 is a plan of a portion of the apparatus constructed in accordance with this invention, showing the position of the can as it is being advanced along supporting rails into a drying station above an upwardly open air jet; and

Fig. 7 is a sectional plan of a pair of jets showing the mechanism by which those jets are simultaneously lifted together into a drying position and retracted therefrom.

In the illustrated embodiment of the invention for the treatment of milk cans, a somewhat box-like housing or frame 1 is supported by suitable legs or brackets 2. Milk cans and their covers to be washed and dried are passed through the housing from end to end and through various positions or stations in which they are washed and rinsed and then dried with air. As shown in Fig. 1, the cans are inverted, with their mouths opening downwardly. They are guided through the various positions or stations in the can washer

by guide rails 4 (Fig. 6) which slidely support the cans, and the cans are shifted from station to station by dogs 5 pivoted on dog bars 6 as is usual in this type of can washer.

Somewhat similar provision is made for guiding the covers through an upper part of the housing, and in the illustrated embodiment in Fig. 1, covers 7 shown in dotted lines roll on the rail 8 and are held in an upright position by the rods 9 and 10 which also extend lengthwise through the housing. The rail 8 has suitable notches or indentations at regularly spaced intervals arresting the covers in proper positions to receive washing fluid or drying air as the case may be. Dogs 11, similar to dogs 5, mounted upon the reciprocating dog bar 12 advance the covers from station to station through the frame.

A rotatable, power actuated shaft 13 (Fig. 1) supplies motive power for the reciprocation of the dog bars 6 and 12 in a manner which will now be described. A disk or cam 14 is mounted on the shaft 13 and has suitably shaped cam surfaces 15 and 16 forming a track or cam groove which engages a roller or cam follower 17 that is pivotally mounted on an arm 18 at a point intermediate of the ends thereof. The arm 18 is pivotally secured by a pin 19 to a stationary support 20 and is oscillated about the pin 19 by the camming action of the surfaces 15 and 16 of the disk against the roller 17. The upper end of the reciprocating arm 18 is pivotally connected to a link 21 (Fig. 1) which is in turn pivotally connected to a pin 21a that is in turn pivotally connected to an arm 21b on a shaft 21c. The arm 21b is articulately connected to dog bars 6, and shaft 21c carries an arm 21d which is articulately connected by link 21e to the cover operating dog bar 12, so that those dog bars 6 and 12 are reciprocated in directions lengthwise of the can washer and in the same general direction as that of the upper end of arm 18 under actuation of the cam disk 14. The details of this dog bar actuation alone form no part of this invention, and are common in the can washer art.

It will be understood that as the dog bars reciprocate in the direction of the advance of a can through the washer, the dogs 5 engage the open ends of the various cans, and since the dogs are confined to a limited clockwise rotation, as shown in Fig. 1, by horizontal flange portions of the dog bars 6 (Fig. 5) they will push against and carry the cans in the direction of advance of the dog bar. The dogs are held in their normal positions shown in Fig. 1 by overweighting the lower ends thereof and as the dog bar 6 is retracted from its advanced position, the upper edge of a dog, upon coming in contact with the lowermost parts of the next can in succession, will be cammed downwardly thereby so that the dog will pass beneath the can and will then assume its normal pushing position upon the other side of the can preparatory for advancing that can forward into its new position. The dogs 11 are similarly operable when the dog bar 12 is shifted lengthwise of the frame for advancing successive covers from one position or station to another through the can washer.

During the time in which the dog bars 6 are being retracted or shifted to the right in Fig. 1 preparatory to the engagement of the dogs with the next can in succession, the cans remain at rest. Thus, the cans are moved by increments from one position or station to the next with relatively short intervals of rest in between. In the earlier stations through which the cans pass, they

are washed and rinsed with streams or sprays of fluid from suitable outlets, such as the outlets 22 (Fig. 1), disposed adjacent the cans while in their positions or stations of rest as is usual in this type of washer. In the last of the stations in the can washer through which the cans are passed, after washing and rinsing in previous stations, they are dried by a stream of warm air usually directed upwardly therein through the open mouths of the cans. Two of such drying stations are shown (Figs. 1, 3 and 4) in which heated air is delivered through the nozzles or delivery pipes 23 and 24 into the cans in the stations above them in a manner which will hereinafter be described.

Air to be used for drying the cans is drawn into the can washer through a screen or filter 25 (Fig. 2) and is then conducted through a suitable heater 26 somewhat diagrammatically shown. The heated air then passes through an air duct 27 into a centrifugal blower or suitable air pump 28. The blower 28, which is driven by a motor 29 delivers air under a relatively low pressure but in substantial volume to a manifold or duct 30 which is advantageously disposed beneath the air nozzles 23 and 24 and extends lengthwise of the path of movement of the cans (Figs. 5 and 7). A pair of upstanding conduits or pipes 31 and 32 are connected at their lower ends to the manifold 30 and extend upwardly and terminate adjacent but below the cans in the drying stations (Figs. 4 and 5), so as to discharge a stream of air upwardly towards the mouths of those cans when at rest in those drying stations. The nozzles or extension members 23 and 24 are telescopically and slidably mounted upon the pipes 31 and 32 and are movable on those pipes in directions lengthwise thereof so that the effective lengths of those pipes may be adjustably extended upwards and the heated air effectively discharged through the upper ends of the nozzles 23 and 24 at a point well within or past the restricted neck of a can into the interior of a can in each of the drying stations as shown in Fig. 4. Since the cans remain in each station only a relatively short time, a considerable volume or quantity of drying air must be quickly circulated through the cans while in each drying station. The air delivery conduits must therefore be of considerable size, and it will be noted that the cross sectional area of the nozzles 23 and 24 is of a considerable size when compared with the area of the restricted mouth or can. Since the air is under relatively low pressure, it will be apparent that an air stream of such size, if merely directed upwardly towards the mouth of the can, would encounter considerable resistance to its passage through that restricted neck since the air leaving the can would tend to meet the stream delivered toward the can in the restricted neck, and a considerable part of the air intended to flow into and delivered toward the can would be deflected aside by the confined body of air within the can and would not penetrate very far into a can without in any way assisting or contributing to the drying of the can. It would not effectively displace the moisture saturated air already within a can and the drying air entering would merely mix somewhat with wet air. This would not create a rapid drying action on the can. When, however, the length of the pipes 31 and 32 is effectively extended so that the stream of air is guided entirely into the can and discharged at a point well above or sufficiently through the restricted neck of a can, the drying air will all tend to flow upwardly into the can and displace the wet air from the can without any

considerable opposition from the air leaving the can, and upon being deflected by the uppermost interior walls of the inverted can, it will flow outwardly and downwardly in intimate contact with the side walls of the can where it is effective in drying the can walls, and finally will leave the can through the area of the neck around the nozzle. The air streams entering and leaving the can will not be intermingled at a restricted point or entrance, and the drying air will therefore effectively come into contact with all the interior walls of the can for a very efficient and rapid drying thereof.

To effect the insertion of the jets or nozzles 23 and 24 into the interior of the cans in the drying stations, a pair of link members or bars 33 and 34 are secured to opposite sides of the lower ends of the nozzles 23 and 24 (Fig. 7) in any suitable manner, such as by pins 35 on the nozzles which loosely engage elongated slots 36 in the links 33 and 34. The bars 33 and 34 are secured together in any suitable manner such as by bolts 37 which pass through spacing members 38 and the bars 33 and 34 and clamp those bars against the spacing members to form a yoke for raising and lowering the jets simultaneously. An arm 39 extending somewhat lengthwise of the path of movement of the cans is fixed on shaft 40 rockably supported by brackets 40a secured to the frame. One end of the arm 39 is pivotally connected to the middle of the yoke formed of arms 33 and 34 in any suitable manner, such as by a pin 41 which is secured to the yoke and passes through a somewhat elongated slot 42 in the arm 39. A weight 43 is secured to the opposite end of the arm 39 for adjustment therewith and yieldingly urges the arm 39 to rotate in a clockwise direction and to raise the nozzles 23 and 24 towards the positions shown in Fig. 4. The weight 43 is sufficiently heavy that when free it will easily raise the nozzles into the Fig. 4 position, but it is also of a size such that an obstruction, for example a misplaced can, which might be in the path of movement of the rising nozzles 23 and 24, would arrest the upward movement of the jets without danger of injury to the can or strain on the mechanism.

In order to retract the nozzles from the cans so that they will be out of the path of movement of the cans while the cans are being advanced from station to station, the apparatus is provided with a positive means for forcibly lowering the nozzles. To this effect, an arm 44 is secured to the shaft 40 for integral rocking movement therewith, as by a key 45 (Figs. 3 and 4). The arm 44 with arm 39 and shaft 40 forms a unit which may be termed a lever. The arm 44 extends generally in an upward direction and carries at its upper end a pin or eye member 46 which is swiveled for rocking movement upon its own axis to the arm 44. A rod or shaft 47 passes transversely through a suitable aperture in the pin 46 in a direction generally lengthwise of the path of movement of the cans and carries at one end thereof a collar or abutment 48. A coil spring 49 is disposed about the rod 47 between pin 46 and collar 48 for engagement against the collar 48 and the pin 46.

When the rod 47 is moved in a direction to compress the spring between the member 46 and the collar 48, it urges the arm 44 and the arm 39 and shaft 40 to rock in a counterclockwise direction about the axis of shaft 40 and thereby lowers or retracts the nozzles from the cans. For this purpose the rod 47 is pivotally connected to one end of a link 50, which is in turn pivotally

connected to crank arm 51 (Fig. 1) secured on the power actuated shaft 13, which is thereby operable to reciprocate the link 50 in directions generally lengthwise of the path of movement of the cans. An arm 52 is pivoted at one end to the pin connecting link 50 and rod 47 and at its other end to the frame. The arm 52 is operable to guide the movements of arm 50 and rod 47 and limit their reciprocations to a prescribed path. It will thus be seen that as the shaft 13 rotates, it will cause the link 50 and rod 47 to reciprocate in one direction, and, through the spring 49 engaging the pin 46, cause a counterclockwise (Figs. 3 and 4) rocking of the arm 39 and retraction of the nozzles. Upon reciprocation of rod 47 in the opposite direction, the compression on the spring 49 is gradually reduced until it is no longer sufficient to overcome the opposing action of the weight 43, and thereupon the nozzles, under the influence of the weight 43, are elevated into the upper or raised positions shown in Fig. 4. It is noteworthy that the shaft 13, as previously mentioned, also drives the dog bars and that the synchronism of the movement of the dog bars and of the retraction of the nozzles from their upper positions is effected by properly adjusting the relatively angular positions of the cam disk 14 and the arm 51 on the power driven shaft 13. The disk 14 and arm 51 may be so adjusted that when the cans are at rest in their quiet positions or treating stations, the rod 47 is reciprocated to the right as shown in Fig. 4, which releases the pin or member 46 from the engagement by and pressure of the spring 49 to permit elevation of the nozzles into the upper positions shown in Fig. 4 by the action of the weight 43. Before the cans are once again advanced by movement of the dog bars, the rod 47 will be reciprocated to the left in Fig. 4 into the position shown in Fig. 3, during which the spring 49 re-engages the member 46, and forcibly rotates the arm 39 in a counterclockwise direction to retract the nozzles from the cans.

45 The covers also are supplied with drying air when in the drying positions corresponding with those of the cans. For this purpose, a branch duct 53 (Figs. 1 and 5) communicates with the manifold 30, extends upwardly and connects with branch pipes 54 and 55 which discharge air against the can covers in a well known manner.

To overcome clashing and noise, and to avoid undue shock and wear on the nozzle actuating parts, there is preferably provided rubber or resilient bumpers or abutments 60, Figs. 3 to 5 which are mounted in sockets 61 secured to the underside of the housing 1. These bumpers 60 are so disposed as to be engaged by the pin 46 as the nozzles 23 and 24 reach their upper positions under the influence of the weight 43 (Figs. 3 and 5), thereby quietly and gently arresting the movement of the parts in this direction. A somewhat similar result is effected by the compression of the spring 49 between the swivel 46 and abutment 48 on rod 47, when the parts move to their extreme opposite or reverse position in shifting the nozzles 23 and 24 to their retracted positions (Fig. 3).

70 As shown and described, the members 33 and 34 of the yoke for imparting simultaneous movement to the two nozzles 23 and 24, are loosely connected to those nozzles and to the slotted end of the lever 39. Since it is desirable that this yoke should maintain an approximately horizontal position at all times in order to main-

tain the discharge ends of the nozzles at the same respective elevations, under all conditions of use, means are provided whereby the yoke is prevented from assuming a substantially tilted position, such as would cause unequal movement and possible binding of the nozzles 23 and 24 relatively to their respective guide or telescopic tubes 31 and 32.

The means shown for this purpose comprises laterally extending wings or projections 65 secured to and extending from opposite sides of the nozzles 23 and 24 in positions closely adjacent the upper edges of the yoke members 33 and 34. Thus, should the yoke, for any reason act to tilt, a relatively slight movement of this kind would cause the upper edges of the members 33 and 34 to engage the wings 65 with the result that tilting of the yoke to an objectionable extent will be prevented and the nozzles actuated in unison and at substantially like elevations.

In order to facilitate assembly of the apparatus, the fan housing 28, the manifold 30, lower section of the duct 53, the nozzles structures and parts of their actuating means are secured together as a unit. On the unit is secured apertured lugs 66, preferably four in number, to the four upper corners of the manifold 30. On the under side of the housing 1 are a corresponding number of fixed depending rods 67, the lower ends of which are threaded and are disposed to extend through the lugs 66 and be stationarily secured thereto as by nuts or other attaching devices, as clearly shown in Figs. 3 to 5 and 7.

The operation of the apparatus briefly is as follows: Cans are fed by suitable means (not shown) into one end of the housing and are advanced through the housing along the rails 4 by means of the dog bars 6 and dogs 5. In Fig. 1, the cans are advanced from right to left and the apparatus is illustrated at a time when the dog bars are just about to be moved from right to left to advance the cans from one position to the next and start a cycle of operations. At this moment, the arm 50 and rod 47, controlled by the crank arm 51, have almost their greatest limit of movement to the left, crank arm 51 is about to pass dead center position, and the spring 49 controlled thereby is compressed against the member 46 and holds the telescoping nozzles 23 and 24 in retracted positions well out of the way of the cans which may be advanced from one station to the next.

As the shaft 13 rotates, the cam disk and the roller 17 cause an advance of the dog bars 6 and the cans pushed thereby. During this advance the spring 49 continues to press against the member 46 and holds the nozzles retracted. After completion of their forward movement, the dog bars 6, under control of the cam disk 14, are immediately reciprocated back toward the right in Fig. 1 into a position for engagement of each of the dogs 5 with another of the successive cans passing through the apparatus. Beginning at this point in the cycle, the cam follower 17 remains stationary while the shaft 13 rotates through an angle of approximately 180 degrees, and during this part of the period of rotation of shaft 13, the cans remain at rest in their respective positions or stations. During the period of rest, however, the link 50 is moved to the right in Fig. 1 to such an extent that compression of spring 49 on pin 46 is reduced, and the spring 49 may even pass entirely out of contact with the pin 46 while the shaft 47 continues its movement toward its limit of move-

ment to the right as shown in Fig. 4 and back again. When spring pressure against pin 46 is sufficiently reduced, the weight 43 operates to oscillate or rock the arm 39 in a clockwise direction and to raise the nozzles into the upper positions shown in Fig. 4. As the shaft 13 continues to rotate and while the dog bars 6 are still at rest, the rod 47 is moved to the left in Fig. 1 until the spring 49 once again engages the pin 46 and causes a withdrawal of the nozzles from their upper positions into their non-obstructing positions shown in Figs. 1 and 3. At this point, the shaft 13 has been rotated through one complete cycle and the apparatus is then set for a repetition of that cycle as previously described.

During the above mentioned cycle of operation, air is drawn into the apparatus through the filter or screen 25 and passes through the heater 26 and duct 27 to the centrifugal blower or fan 28. The heated air is then discharged therefrom into the manifold 30 and flows continuously through the conduits 31 and 32 and the nozzles or members 23 and 24 to effect the drying of the cans. Another stream of air is discharged from the manifold 30 through the conduit 53 and branches 54 and 55 against the covers in their respective drying stations. It will be understood, of course, that the covers also are advanced through the respective stations by operation of the dog bar 8 and the dogs 11 in a well known manner.

One will observe that the apparatus constructed in accordance with this invention provides for most effective use of heated air in large volume under relatively low pressure for drying cans and covers in a can washer, and that such drying will be accomplished quickly and efficiently, and without the added expense which is attendant upon use of air under high pressure or the slowing down of the cycle of operations to allow a much longer treatment of the cans in the drying stations.

It will be obvious that various modifications of the details which have been herein described and illustrated in order to explain the nature of the invention, may be made by those skilled in the art within the principle and scope of the invention as expressed in the appended claims.

We claim as our invention:

1. Improved apparatus for drying a hollow container having a restricted opening communicating with the interior thereof with an injected stream of gas of relatively large cross sectional area with respect to the area of said opening, which comprises means for advancing said container through a drying station with a period of rest in that station, a source of drying gas under pressure, a conduit connected to said source and having an outlet end adjacent said station for delivery of drying gas therethrough to the opening in said container when in said station, a tubular discharge extension member telescopically connected to said end of said conduit and shiftable lengthwise along said conduit while in telescopic relation therewith for selectively increasing and decreasing the effective length thereof, means for yieldingly urging said member in a direction outwardly along said conduit into a drying position in which said member extends through the restricted opening of said container substantially into the interior of said container while said container is in said station, and means operable in timed relation to said advancing means for positively retracting said member from said position before said container leaves said

station whereby a stream of drying gas will flow effectively through the interior of said container when in said station.

2. Improved apparatus for drying a hollow container having a restricted opening communicating with the interior thereof with an injected stream of gas of relatively large cross sectional area with respect to the area of said opening, which comprises means for advancing said container through a drying station with a period of rest in that station, a source of drying gas under pressure, a conduit connected to said source and having an outlet end adjacent said station for delivery of drying gas therethrough to the opening in said container when in said station, a tubular discharge extension member telescopically connected to said end of said conduit and shiftable lengthwise along said conduit while in telescopic relation therewith for selectively increasing and decreasing the effective length thereof, means yieldingly urging said member outwardly along said conduit towards a drying position in which said member extends through the restricted opening of and substantially into the interior of said container when in said station, and retraction means for withdrawing said member back along said conduit from said drying position and holding said member in a position in which it will not obstruct the advance of said container while said container is moving into and out of said station.

3. In a can washer of the type in which the washed cans are passed through a drying station in which a stream of gas of relatively large cross sectional area with respect to the area across the neck of a can is injected into said cans, the improvement which comprises a power actuated member, a source of heated gas under relatively low pressure, a conduit connected to said source and having an open discharge outlet adjacent said drying station, means driven by said member for advancing a can into said drying station, means yieldingly urging said conduit outlet through the neck of said can into a drying position substantially within said can while in said station, means driven by said member for advancing said can out of said station after said can has remained an interval at rest therein, and means driven by said member in timed relation to said advancing means for retracting and holding said conduit outlet retracted from said drying position and out of the path of movement of said can while said can is advancing into and out of said station, whereby drying gas will effectively flow throughout the entire interior of said can in said station.

4. Improved apparatus for drying a hollow container having a restricted passageway communicating with the interior thereof which comprises means for advancing said container into a drying station, leaving said container at rest in said station during an interval, and then advancing said container out of said station, a source of drying gas under pressure, a tubular conduit connected to said source and having an outlet terminal disposed adjacent to said station and extending towards the passageway of said container when at rest in said station, a tubular discharge spout telescopically connecting with said terminal to receive fluid passing therethrough and mounted for telescopic movement with respect to and lengthwise of said terminal, means for continuously and yieldingly urging said spout outwardly from said conduit into a drying position in which said spout extends through said

passageway and discharges at a point substantially within said container at rest in said station, and power actuated means for retracting said spout from said drying position and holding it out of the path of movement of said container while said container is moving into and out of said station.

5. In a can washer of the type in which inverted cans are guided along an approximately horizontal path through drying stations in which a stream of drying gas of relatively large diameter with respect to the diameter of the neck of a can is injected through said neck into said can, the improvement which comprises means for advancing said cans in succession into a drying station, leaving said cans at rest in said station during an interval of time, and then removing said cans from said station, a source of drying gas under pressure, a conduit in communication with said source, said conduit having a discharge tube extending upwardly adjacent said station in a direction toward the mouth of any can when at rest in said station, a tubular extension member telescoping with said discharge tube and movable lengthwise with respect thereto for increasing and decreasing the effective length of said discharge tube, means operable when released for shifting said telescoping member upwardly along said tube through the neck of and substantially into the interior of a can at rest in said station, whereby said conduit will effectively discharge a stream of drying gas at a point substantially within said can, and means for retracting said member downwardly out of the path of movement of said can, holding it retracted for an interval during which said cans are advanced, and then releasing it.

6. In a can washer of the type in which inverted cans are guided along an approximately horizontal path through a drying station in which a stream of drying gas of relatively large diameter with respect to the diameter of the neck of a can is injected through said neck into said can, the improvement which comprises means for advancing said cans in succession into said drying station, leaving said cans at rest in said station during an interval of time, and then removing said cans from said station, a source of drying gas under pressure, a conduit in communication with said source, said conduit having a discharge tube extending upwardly adjacent said station in a direction toward the mouth of any can when at rest in said station, a tubular extension member telescoping with said discharge tube and movable lengthwise with respect thereto for increasing and decreasing the effective length of said discharge tube, means yieldingly urging said member upwardly along said tube into a drying position in which it discharges at a point substantially within said can when at rest in said station, and power actuated means operable in timed relation with said advancing means for retracting said member downwardly out of the path of movement of said can, and holding said member in retracted position while said can is moving into and out of said station, and then releasing it.

7. In a can washer of the type in which inverted, open mouth cans are guided along a substantially horizontal path through a plurality of washing and drying stations, the improvement which comprises, means for advancing each of said cans into successive drying stations, leaving said cans at rest during an interval of time in each of said stations and advancing said cans

out of each of said stations, a source of drying gas under relatively low pressure, a pipe extending upwardly toward and terminating adjacent one of said drying stations, and having an open end for the emission of drying gas toward a can in said station, another pipe similarly terminating adjacent another of said drying stations, means for connecting the other ends of said pipes to said source, a tubular extension member telescopically connected to the said terminal end of each of said pipes, and shiftable lengthwise of said pipes into and out of drying positions in which each of said members extends substantially through the neck and into the interior of a can at rest in each of said stations, whereby drying gas may be effectively circulated through said cans, an element connecting said members for movement therewith, means yieldingly urging said element in a rising direction, and means operable in timed relation to the advancement of said cans through said stations for forcibly lowering said element and holding it lowered while said advancing means operates to advance the cans, and then releasing it.

8. Improved apparatus for drying a hollow container having a restricted aperture therein which comprises a source of heated air under relatively low pressure, a pipe connected with said source and having a discharge end opening upwardly, means for advancing said container into a station above said discharge end in which said pipe discharges towards said aperture, means for yieldingly urging relative approach of said discharge end and said container in a direction to insert said discharge end entirely through said aperture into said container, and means operable to forcibly withdraw it out of the interior of said container; and means for advancing said container out of said station while said discharge end is entirely outside of said container.

9. Improved apparatus for drying the interior of a hollow container having an opening therein, which comprises means for advancing a container through a drying station, a source of drying gas under pressure, a conduit connected to said source and having a discharge outlet adjacent said station for delivery of a stream of drying gas therethrough into said container, means operable in timed relation to said advancing means for yieldingly inserting said outlet of said conduit through the opening in said container and a substantial distance into the interior thereof while said container is in said station and for forcibly removing said outlet from said container before it leaves said station, whereby drying gas passing through said outlet will flow in intimate contact with the inner walls of said container.

10. Improved apparatus for drying the interior of a hollow container having an opening therein, which comprises means for advancing a container through a drying station, a source of drying gas under pressure, a conduit connected to said source and having a discharge outlet adjacent said station for delivery of a stream of drying gas therethrough into said container, said conduit outlet being mounted for movement into and out of a drying position substantially within said container when in said station, means for yieldingly urging said outlet toward said drying position, and means operable in timed relation to said advancing means for retracting, and holding retracted, said outlet from said drying position while said container is entering and leaving said station, and then releasing it where-

by said container may be thoroughly dried by gas flowing in intimate contact with the interior walls thereof.

11. A machine for drying the interiors of cans having substantially restricted open mouths, which comprises means for conveying said cans in succession and in inverted positions along a prescribed path, with intervals of rest at selected points in said path representing treating stations, a source of drying gas under relatively low pressure, a pipe connected to said source and having a discharge end disposed below said path at one of said stations and discharging upwardly into the mouth of an inverted can in that station a stream of said drying gas, and means operable in timed relation to the movement of the cans along said path for yieldingly urging the discharge end of said pipe through the restricted mouth of any can in said station while that can is substantially in said station, and for forcibly removing it fully from said container and holding it removed during the interval whenever there is any movement of the cans along said path.

12. A machine for drying the interiors of cans having substantially restricted open mouths, which comprises means for conveying said cans in succession and in inverted positions along a prescribed path, with intervals of rest at selected points in said path representing treating stations, a source of drying gas under relatively low pressure, a pipe connected to said source and having a discharge end disposed below said path at one of said stations and discharging upwardly into the mouth of an inverted can in that station a stream of said drying gas, means normally urging the discharge end of said pipe yieldingly and continuously in a direction upwardly through the restricted mouth of any can in said station, means operable in timed relation to the movement of said cans along said path for normally holding said terminal below said path during movement of said can conveying means and for releasing said terminal for upward movement while the conveying means is inactive, whereby the stream of gas then entering a can into which the terminal discharges may rise to the top of the interior of the inverted can and displace all of the air within the can with said drying gas, and for then lowering said discharge end below said path before said cans are moved along said path, and holding it lowered until the can movement has been completed.

13. Improved apparatus for drying the interiors of hollow containers having relatively restricted open mouths, which comprises means for conveying said containers in inverted positions along a selected path in a step by step movement, with substantial intervals of rest between movements so as to convey said inverted containers in succession through treating stations with periods of rest in said stations, a source of drying gas under pressure, a pipe connected to said source and disposed beneath said path at one of said stations and directed upwardly towards the open mouth of any container in that station, a nozzle telescoping with said pipe and movable thereon into and out of the restricted mouth of any container in said station, the extent of movement being sufficient to carry the discharge end of said nozzle substantially through the restricted open mouth, means yieldingly and continuously urging said nozzle upwardly into any container in said station, and means operable in timed relation to the movement of said cans

and operable to positively pull said nozzle downwardly below said path during the interval of movement of said cans along said path and to release it during the interval between such movements.

14. Improved apparatus for drying the interiors of hollow containers having relatively restricted open mouths, which comprises means for conveying said containers in inverted positions along a selected path in a step by step movement, with substantial intervals of rest between movements so as to convey said inverted containers in succession through treating stations with periods of rest in said stations, a source of drying gas under pressure, a pipe connected to said source and disposed beneath said path at one of said stations and directed upwardly towards the open mouth of any container in that station, a nozzle telescoping with said pipe and movable thereon into and out of the restricted mouth of any container in said station, the extent of movement being sufficient to carry the discharge end of said nozzle substantially through the restricted open mouth, a lever mounted for rocking movement, means connecting said lever to said nozzle for causing elevation and lowering of said nozzle upon oscillation of said lever, means urging said lever yieldingly to rock in a direction to elevate said nozzle, a pin mounted on said lever for rocking movement therewith and having an aperture therethrough from face to face, a rod slidably passing through said aperture and having an abutment, a spring on said rod between said abutment and said pin, means connected to said rod and operable in timed relation to the conveying means for operating said rod endwise in one direction to compress said spring against said pin and through the spring rock said lever in a direction to cause a lowering of said nozzle and hold it lowered during the interval in which said conveying means is advancing containers from station to station, and in the opposite direction to shift said rod through said pin, release said pin from the action of said spring sufficiently to enable a rocking of said lever in a direction and for a distance to elevate said nozzle through said open mouth of a container thereabove between container advancing movements of said conveying means.

15. Improved apparatus for drying the interiors of hollow containers having relatively restricted open mouths, which comprises means for conveying said containers in inverted positions along a selected path in a step by step movement, with substantial intervals of rest between movements so as to convey said inverted containers in succession through treating stations with periods of rest in said stations, a source of drying gas under pressure, a pipe connected to said source and disposed beneath said path at one of said stations and directed upwardly towards the open mouth of any container in that station, a nozzle telescoping with said pipe and movable thereon into and out of the restricted mouth of any container in said station, the extent of movement being sufficient to carry the discharge end of said nozzle substantially through the restricted open mouth, a lever mounted for rocking movement, means connecting said lever to said nozzle for causing elevation and lowering of said nozzle upon oscillation of said lever, means urging said lever yieldingly to rock in a direction to elevate said nozzle, a pin mounted on said lever for rocking

movement therewith and for independent oscillation thereon about an axis parallel to the oscillation axis of said lever, and having an aperture therethrough from face to face, a rod slidably passing through said aperture and having an abutment, a spring on said rod between said abutment and said pin, means connected to said rod and operable in timed relation to the conveying means for operating said rod endwise in one direction to compress said spring against said pin and through the spring rock said lever in a direction to cause a lowering of said nozzle and hold it lowered during the interval in which said conveying means is advancing containers from station to station, and in the opposite direction to shift said rod through said pin, release said pin from the action of said spring sufficiently to enable a rocking of said lever in a direction and for a distance to elevate said nozzle through said open mouth of a container thereabove between container advancing movements of said conveying means.

16. Improved apparatus for drying the interiors of hollow containers which comprises power operated means for conveying said containers along a selected path successively through a drying station in a step by step movement, with substantial intervals of rest between movements, a source of drying gas under pressure, a tube, means connecting said source to said tube, means supporting said tube and any container in said station for relative movement in a direction to cause entry of said tube into said container in said stations and its retraction therefrom, a crank operated by said power operated means in timed relation thereto, an arm for causing said relative movement of the tube and container, means urging said arm in a direction to cause entry of said tube into said container in said station, and connecting means acting between said arm and said crank for forcibly moving said arm in a direction to cause relative removal of said tube from said container in said drying station during one portion of each revolution of said crank, for releasing said arm in another portion of said revolution, and for holding said arm in tube withdrawn position during continued movement of said crank in another portion of each revolution following each relative withdrawal of said tube from said container in drying position.

17. Improved apparatus for drying the interiors of hollow containers which comprises power operated means for conveying said containers along a selected path successively through a drying station in a step by step movement, with substantial intervals of rest between movements, a source of drying gas under pressure, a tube, means connecting said source to said tube, means supporting said tube and any container in said station for relative movement in a direction to cause entry of said tube into said container in said station and its retraction therefrom, a crank operated by said power operated means in timed relation thereto, an arm for causing said relative movement of tube and container, means yieldingly urging said arm in a direction to cause entry of said tube into said container in said station, and means operatingly connecting said crank and arm to cause said relative retraction of said tube against the action of said urging means under the force transmitted by said crank.
